UNITED STATES PATENT OFFICE.

GEORGE W. HOWES, OF DOWAGIAC, MICHIGAN, ASSIGNOR TO ESTATE OF P. D. BECKWITH, INC., OF DOWAGIAC, MICHIGAN.

DESIGN FOR A HEATING-STOVE.

46,094.

Specification for Design.

Patented July 14, 1914.

Application filed February 26, 1914. Serial No. 821,306. Term of patent 14 years.

To all whom it may concern:

Be it known that I, GEORGE W. HOWES, a citizen of the United States, and a resident of Dowagiac, county of Cass, State of Michigan, (whose post-office address is Dowagiac, Michigan,) have invented a new, original, and ornamental Design for Heating-Stoves, of which the following is a specification, reference being had to the accompanying drawing, forming a part thereof.

The figure is a perspective view of a heating stove showing my new design.

I claim:

The ornamental design for a heating stove as shown.

GEORGE W. HOWES.

In the presence of—

HARRY W. PALMER,

HARRY C. MOSHER.
